METHOD AND APPARATUS FOR
MINING SULPHUR

Lawrence O'Donnell, Houston, Tex.

Application March 1, 1935, Serial No. 8,914

7 Claims. (Cl. 262—3)

This invention relates to the mining of soluble materials, and especially to an improved method and apparatus for mining sulphur.

In certain known localities, there exist the geological conditions and arrangements shown in the accompanying figure of drawings in which a section of the earth is shown in connection with the mining apparatus in a conventional or diagrammatic way.

Heretofore, the mining of sulphur has been accomplished by drilling down into the sulphur-deposit, forcing super-hot water into the deposit for melting the adjacent sulphur, then pumping or otherwise forcing the melted sulphur up into the receptacle where the sulphur solidifies to thereafter be removed for shipment and use. Here, it should be understood that the term super-hot means not only above the boiling point at atmospheric pressure, but as used herein, it also means above the melting point of native sulphur. While that previous method accomplished a limited degree of success, the cost of super-heating the water and maintaining its temperature above the melting point of sulphur throughout each cycle was found to be quite expensive and to require great vigilance in operating the plant to prevent the sulphur from solidifying in the delivery pipe that leads to the receptacle where it is left to cool and solidify.

Therefore, in Patent No. 1,814,539, it was proposed to use as the sulphur-melting agent a brine or aqueous solution of sodium-chloride, instead of pure (non-saline) water, so as to increase the density of the melting fluid (for purposes stated in that patent), and for raising the boiling point of such fluid; but since the normal boiling point of a saline solution or brine is less than the melting point of sulphur, it was proposed to subject the sulphur-melting agency to pressure of a sufficient degree to raise the temperature to about 240° F. or up to 340° F., according to various and varying conditions of the sulphur-deposit; for obviously, the more ground-water encountered in the sulphur deposit, the more heat will be required to overcome the cooling tendency of the same. However, less pressure is required to keep the brine at a given degree of super-heat than is required for pure water, for the latter tends to be converted into steam at a temperature far below the melting point of sulphur and to pass away into the adjacent parts of porous deposits of sulphur and other materials; hence, less power is required to supply the pressure to the brine than to the super-heated pure water.

However, varying and various conditions re-

quire, for best results, variations in the proportion of salt in the water used for melting the sulphur; and it has heretofore been found difficult and expensive to effect the necessary changes or variations, also expensive to supply the salt and to mix it with the water, so—

One object of this invention is to provide an apparatus that supplies the brine ready-mixed and in a highly heated condition direct from a salt-mine subjacent or adjacent to the sulphur mine, and thereby eliminate the trouble and expense of obtaining, mixing and varying the salt-content and of heating it in a container that would be detrimentally affected thereby.

Another object is to provide valved pipe connections between the water-heater and the well-casings and supply and delivery tubes in a practical relation for varying the density or saltiness of the brine by manipulating the valves according to various and varying requirements.

Other objects and important features are pointed out or implied in the following description, in connection with the accompanying drawing.

In the drawing, the upper stratum of earth is indicated at E; the cap-rock of limestone, at C; a stratum of anhydrite and gypsum, at A—G; a deposit of native sulphur, at S; a pocket of melted sulphur and super-hot water, at S—W; a lower stratum of salt or sodium-chloride, at S—C; and a pocket of super-hot brine, at S—C—W.

Although, in some instances, these natural deposits are under water, as at Lake Piegneur, La., so the mining apparatus (in whole or in part) is supported on or in the water, the present apparatus is shown on dry land and consists of co-operative parts described as follows:

A well-casing 1 extends down into a well 2, through the strata E and C and terminates in the sulphur deposit S or in the solution S—W, and has a sulphur-delivery pipe 3 extending therethrough and helping to seal it at its upper end. A second well-casing 4 extends down through a well 5 which goes through the strata E, C, S, A—G and terminates in the salt deposit S—C, preferably at a distance far below the earth's surface where the inherent temperature is relatively great, also increasing the pressure in consequence of the pressure-head in the well casing, and thereby raising the temperature so as to minimize the essential power applied to the pressure-pump that connects to the water-heater 7 through a main supply pipe 8, and to the casing 4 through a pump-delivery pipe 9.

A brine-raising pipe 10 extends through the

well-casing 4, helping to seal the top of the latter, and connects with a suction pump 11 whose outlet pipe 12 is in open communication with the well-casing 1. The pump 11 may be dispensed with under certain conditions, and may be such that water can be forced through it by external pressure.

A fresh-water pipe or by-pass conduit 13 communicates with the water-heater 7 and the pipe 10 through valves 14 and 15 which are operable to regulate the rate of flow or to entirely cut off the flow through this pipe. Between the valves 14 and 15, a pressure-transfer pipe 16 is in communication with the pipe 13, and also communicates with the pipe 9 at a point between the pump 6 and the casing 4. This pipe 16 is provided with a valve 17 for regulating the rate of flow therethrough or for entirely cutting off the flow, according to requirements under various and varying conditions.

Each casing 1 and 4 is provided with a seal or a plurality of seals, as indicated at 18, 19 and 20, to prevent the solutions from flowing upward therearound and decreasing the pressure in the pockets containing the solutions; also to prevent the pressure from raising the comparatively short and light-weight casing 1. These seals may be provided in any appropriate way, for instance, when drilling the wells, at the time the drilling tool enters the sulphur deposit, super-hot water is forced into said deposit so as to melt away the adjacent sulphur from a pocket to be filled with portland cement after the casing is properly placed in the well. A similar operation is performed when the drilling tool has passed into the salt-deposit, and such seal may be either at the top of the deposit, or at any desired place therein.

The operation is as follows: When the fresh or non-saline water in the water-heater 7 has attained a temperature of from 300° F. to 400° F., or even higher, all the valves being closed, the pump 6 is then operated (by any appropriate means) and begins to force super-hot water into the salt-deposit S—C, so as to dissolve some of the salt and form a hot brine and at the same time build up a pressure that maintains or increases the temperature of the brine; next, the pump 11 is started to operate and to cooperate with the pressure in the brine-raising pipe 10 for delivering the super-hot brine into the casing 1 and thence to the sulphur-deposit S so as to melt the adjacent sulphur. If there is cold non-saline or slightly saline ground-water in the sulphur deposit, the super-hot brine (being lighter than the cold water) immediately rises to the top and spreads to the sides of the cavity or pocket S—W and melts the sulphur thereat, so the melted sulphur (being heavier) precipitates to the bottom of the pocket to be passed upward through the pipe 3. The ground-water soon becomes mixed with the super-hot brine and partakes of the heat and the salt thereof, so that, by making the brine sufficiently hot and salty, the whole mass of water in the pocket S—W becomes effective in melting the sulphur from all sides of the pocket or cavity, upper, lower and lateral. As the sulphur is forced out from the bottom of the pocket, through pipe 3, by pressure and/or other means, more room is provided in the pocket for super-hot brine to keep up the sulphur-melting temperature. From the pipe 3, the melted sulphur flows into the tank or receptacle 21 which may have at least one removable wall, so easy access can be had to the solidified sulphur; and so the

same can be broken, removed and loaded for shipment.

Variations in operation are necessary for various fields of operation and for changes that take place during a long-continued operation; for instance, as the pockets increase in size, the more heat is absorbed by the surrounding earthen materials, so more heat must be applied to the sulphur-pocket to insure keeping the sulphur from solidifying in the pipe 3; so, by opening the valves 14 and 15, non-saline super-hot water can be supplied or by-passed independently of the casing 4, direct from the water-heater to the intake of the pump 11, or, by a slight change of pipe connections, direct to the well-casing 1, thereby not only raising the temperature of the sulphur-melting brine, but also diluting it while retarding its flow through the brine-pipe 10. However, if the pressure in the pipe 10 is greater than that in the pipe 13 so as to cause back-pressure in the latter in consequence of the force-pump 6, the valve 14 may be closed and the valve 11 opened, thereby dividing the force of the pump 6 between the pipe 16 and the outlet of the pipe 9, so this pump then simultaneously forces brine through the pipe 10 and pure super-hot water through the pipes 16—13 into the brine-current so as to simultaneously dilute and super-heat the brine, or raise its temperature to extra-superheat. This dilution of the brine is of importance 30 for preventing it from becoming too dense and heavy; for a perfectly saturated solution is produced in the pocket S—C—W, inasmuch as the super-hot water holds the maximum of salt in solution at a given pressure; so if this saturated 35 solution is delivered into the pocket S—W, the salt begins to precipitate as the water cools and to mix with the sulphur as the latter precipitates; but by diluting the brine with pure water, it holds the salt in suspension while the sulphur precipitates to the mouth of the delivery pipe 3.

I do not intend to limit my patent protection to the precise details of construction, arrangement or method here shown and described, for the invention is susceptible of numerous modifications 45 within the scope of the inventive ideas as implied and claimed.

What I claim as my invention is:

1. The method of mining sulphur from a geological sulphur deposit adjacent to a geological 50 salt deposit, consisting in forcing super-hot water into the salt deposit and thereby creating a brine while applying pressure to maintain the heat above the melting temperature of sulphur and forcing the super-hot brine from the salt 55 deposit to the sulphur deposit so as to melt the adjacent sulphur and hold it suspended in the hot brine and to utilize the pressure for forcing the brine and suspended sulphur out of the geological sulphur deposit. 60

2. The method of mining sulphur from a geological sulphur deposit adjacent to a geological salt deposit, consisting in forcing hot water into said salt deposit and thus forming a saturated saline solution while applying pressure to force the saturated saline solution in a current that passes to said geological sulphur deposit, and forcing a non-saline super-hot current of water into the saturated saline current so as to dilute the saturated saline current and raise its temperature above the melting point of sulphur so as to melt the adjacent sulphur and intermix it with the diluted saline solution while maintaining a pressure sufficient to keep the sulphur melt- 70 75

ed and to force the melted sulphur and saline solution out of said geological sulphur deposit.

3. In an apparatus for mining sulphur from a geological sulphur deposit adjacent to a geological salt deposit, the combination of a well-casing extending into said sulphur deposit, a sulphur-delivery pipe extending into said sulphur deposit, a well-casing extending into said salt deposit, a brine delivery pipe extending into said salt deposit and being in open communication with the first said well casing so as to conduct a saline solution from said salt deposit to said sulphur deposit, a water heater which is effective to heat water and maintain a pressure sufficient to produce super-hot water at a temperature above the melting point of sulphur and means to conduct the super-hot water into the second said well casing under pressure sufficient to force it through this well casing into said salt deposit and to maintain a high pressure for producing a super-hot saline solution and to force the latter through the said brine conducting pipe and the first said well casing into said sulphur deposit for melting adjacent sulphur and forcing the melted sulphur and super-hot saline solution out of the sulphur deposit by way of the sulphur conducting pipe.

4. In an apparatus for mining sulphur from a geological sulphur deposit adjacent to a geological salt deposit, the combination of means to produce a super-hot saturated saline solution within said geological salt deposit, and means to conduct said saturated saline solution from said salt deposit toward said sulphur deposit, means being provided in conjunction with the first said means and second said means to dilute and raise the temperature of said saturated solution and to force the diluted highly heated solution into said sulphur deposit with sufficient heat and pressure to melt the adjacent sulphur and cause a current of the melted sulphur and solution to flow out of said sulphur deposit.

5. In an apparatus for mining sulphur from a geological sulphur deposit which is adjacent to a salt deposit; the combination of means to super-heat water above the melting temperature of sulphur and maintain a pressure for sustaining said temperature above said melting point, means to conduct a current of water from said heater into said salt deposit and thereby create a saturated saline solution in said salt deposit, means to

duct a current of the saline solution out of said salt deposit into cooperative relation to said water heater, a well casing in open communication with the last said means and extending into said sulphur deposit, a pipe extending from said water heater to the third said means and in open communication therewith so as to conduct super-hot non-saline water to the saline solution for diluting the latter and raising its temperature as it flows towards the sulphur deposit, said pipe being provided with means to regulate the flow of non-saline water therethrough and to stop said flow, a pressure pump operatively connected to the second said means so as to increase the pressure of the saline solution in said salt deposit, and a valved pipe in open communication with the first said pipe and with the second said means, the valve of the second said pipe being operable for opening and closing the pipe, the first said pipe being provided with a closing valve between the second said pipe and the third said means, whereby a current of water can be by-passed from said water-heater into the second said means independently of said pump.

6. In an apparatus for mining sulphur from a geological sulphur deposit which is adjacent to a deposit of brine, the combination of means to conduct the brine into a sulphur deposit, means to apply pressure and conduct heat simultaneously to the brine in a proper manner and degree to melt the adjacent sulphur so it mixes with the brine and passes therewith from the sulphur deposit under the urge of said pressure, and means to dilute the brine with super-hot non-saline water during its passage into said sulphur deposit. 35

7. In an apparatus for mining sulphur from a geological sulphur deposit which is adjacent to a deposit of brine, the combination of means to conduct the brine into said sulphur deposit, means to supply pressure to the brine for raising its temperature and causing it to flow through the first said means into said sulphur deposit, means in cooperative relation with the first and second said means for diluting and super-heating the brine while being conducted to said sulphur deposit so as to melt adjacent sulphur and hold it in suspension, and means to conduct the diluted brine and melted suspended sulphur from said sulphur deposit under urge of said pressure. 40 45
